GARMENT ENVELOPE

Samuel Reich, Brooklyn, N. Y.

Application June 11, 1934, Serial No. 729,964

2 Claims. (Cl. 229—87)

This invention relates to improvements in garment envelopes, and more particularly to envelope holders for preserving the laundered condition of men's shirts when new and placed in stock, or when returned to a customer from a laundry.

One of the objects of the invention resides in an envelope wrapper which is open at opposite ends, there being means formed from the material from which the envelope is constructed for preventing the accidental shifting or sliding of a shirt from either end thereof.

Another feature of the invention is to provide a double envelope or holder for receiving two shirts in back to back relation, the article being constructed of a single blank of folded material.

A further feature is the provision of a shirt envelope constructed of cardboard having the top of one of its walls shaped to fit beneath the outer fold of the collar of a laundered shirt which prevents sliding of the shirt in one direction when placed in the envelope, while a bendable flap is struck out from the outer wall and adapted to be folded over the front of the collar to prevent sliding of the shirt in an opposite direction.

A still further object is to provide a shirt envelope which is simple and inexpensive of construction, and which holds a shirt in a neat and attractive condition.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a front elevational view of my improved garment envelope showing a man's shirt in position therein.

Figure 2 is an enlarged detail vertical sectional view on the line 2—2 of Figure 1.

Figure 3 is a fragmentary perspective view of one end of the envelope.

Figure 4 is a horizontal sectional view on the line 4—4 of Figure 3.

Figure 5 is a horizontal sectional view showing a slight modification.

Figure 6 is a fragmentary front elevational view of another modification.

Figure 7 is a front elevational view of a still further modified form.

Figure 8 is a horizontal sectional view of another modification.

Referring to the drawing by reference characters, the numeral 10 designates the preferred

form of my shirt envelope in its entirety which in Figures 1 to 4 inclusive, discloses a construction wherein the article is made of a single piece of folded cardboard. By reference to Figure 4, it will be seen that the single blank of material is folded to provide a central body portion 11, one side of the body portion having a side flap 12 extending at right angles therefrom, while a right angle fold 13 extends from the opposite side of the body 11, whereupon the material is again folded to provide an outer wall 14, thence the material is folded to provide a narrow edge wall 15 to which the flap 12 is adhesively secured. The blank of material after forming the edge wall 15 is extended parallel to the body portion 11 and in spaced relation thereto to provide an outer wall 16, whereas the remaining free edge of the blank is folded at right angles to lie against the wall 13 to which it is adhesively secured. By constructing the article in this manner, two separate shirt receiving compartments or pockets 17 and 18 are provided.

The opposed outer walls 14 and 16 terminate short of opposite ends of the body portion 11 to provide a backing for the full length of a laundered shirt when inserted into position within the pockets 17 and 18.

Both opposed walls 14 and 16 are formed with a means for preventing the longitudinal shifting of shirts when inserted into the pockets 17 and 18, and a description of a single means will suffice for the other. I shall describe in detail, the shirt retaining means contained on the outer wall 16 but identical means is provided on the wall 14, but at an end of the said wall opposite to that end on which the holding means is shown on the wall 16.

The upper edge of the outer wall 16 is formed with a substantially V-shaped cutout to provide two extension flaps 20—20, there being a crotch 21 therebetween. Cut from the wall 16 just inwardly of the crotch 21, is a tongue 22 which is adapted to be bent outwardly and upwardly over the front of the collar of the shirt contained within the compartment or pocket 18 in a manner now to be explained.

The normal position of the envelope is shown in Figure 3 and is ready to receive a pair of shirts respectively in the pockets or compartments 17 and 18. In practice a shirt A is inserted in a folded condition into the pocket 18 with the folded end first, said shirt being inserted into that end of the pocket adjacent which the shirt holding means is provided. After being fully inserted into the pocket, the front collar flaps B—B respectively overlie the extension tabs 20—20, thus pre-

venting the shirt from shifting longitudinally in one direction. To prevent the shirt from shifting longitudinally in an opposite direction, the tongue 22 is folded over the front of the collar 5 so that the free end of the tongue extends into the compartment 18 as best seen in Figure 2 of the drawing. When the tongue 22 is thus folded, it remains in such condition due to the inherent characteristics of the cardboard. Thus it will be 10 seen that the extension tabs 20—20 engaging beneath the outer flaps of the collar of the shirt and the tongue 22 coacts to prevent accidental shifting of the shirt lengthwise of the envelope. When a shirt is similarly inserted into the other pocket 17, 15 it will be seen that the bulky ends of the shirt are disposed at opposite ends of the envelope to facilitate compact stacking of the wrapped shirts.

In Figure 5 of the drawing, the same construction is shown as is present in Figures 1 to 3 with 20 the exception that the main body portion 11' is of a single piece of material, whereas the outer walls are constructed of a separate folded blank of material 23. In this construction the body portion or partition 11' is provided with flaps 24 25 which are adhesively secured to the opposite edge walls of the outer wall structure 23.

Although I have illustrated a double type envelope in the form of my invention just described, it will be understood that the same may be 30 constructed of a single shirt receiving pocket if desired.

In Figure 6 of the drawing, there is shown a modified form of envelope of the single type which includes a rear wall 25 having an extension tab 35 26 projecting from one end thereof. A front wall 27 is secured to the rear wall at opposite sides thereof to form the open ended envelope and has its end adjacent the tab 26 cut into substantially V-formation to conform to the shape of the folded 40 edge of the collar of a shirt when in position within the envelope. The collar in this form underlies the front wall 27 and to simulate the front outer folds of an underlying collar, the front wall is slit as at 28 to provide collar shaped flaps 29. The 45 front wall 27 is provided with a struck out tongue 30 similar to the tongue 22 in the preceding form. In this form of the invention, the folded shirt is inserted into the envelope and the tab 26 is positioned beneath the outer fold of the collar at the 50 rear thereof, while the front collar folds underlie the collar shaped portions 29. The tongue 30 is bent outwardly over the crotch of the V-shaped cut out to engage the inside of the collar at the front thereof.

55 In Figure 7 I have shown a construction somewhat similar to that shown in Figure 6 and like reference characters refer to similar parts. However, the front wall 27 is cut away to expose the collar and the same is provided with a window

opening closed by a transparent covering 34 of cellophane, glassine, or like material to expose the bosom portion within the envelope. The shirt is held against accidental longitudinal shifting by the tongue 30 and tab 26 in the manner hereinbefore described. 5

In Figure 8 of the drawing, a construction similar to that shown in the preceding form is illustrated, wherein the envelope is constructed of a single blank of cardboard 31 having its free ends 10 lapped as at 32, and adhesively secured together. The edge walls of the envelope are provided with accordion folds 33 so that the envelope may be folded flat when not in use and opened to the desired degree to accommodate the thickness of 15 the shirt inserted therein.

While I have shown and described what I consider to be the most practical embodiments of my invention, I wish it to be understood that such changes as come within the scope of the ap- 20 pended claims may be resorted to if desired.

Having thus described the invention, what I claim as new and desire to secure by Letters Patent of the United States, is:—

1. A shirt envelope comprising a cardboard 25 envelope body open at one end, the front wall of said envelope body at the open end thereof being provided with a notch having converging side walls for exposing the neck of a shirt when inserted into said envelope body, and a tongue cut 30 from the front wall of said envelope body adjacent to and inwardly of the base of said notch and in alignment therewith for folding through the notch and downwardly upon itself to lie inside of said envelope body and adapted to engage 35 the exposed neck end of a shirt when a shirt is in position within said envelope body.

2. A shirt envelope comprising a cardboard envelope body open at opposite ends, the front wall of said envelope body at one end being provided 40 with a notch having converging side walls for exposing the neck band of a shirt when inserted into said envelope body, a tongue cut from the front wall of said envelope body adjacent to and inwardly of the base of said notch and in 45 alignment therewith for folding through the notch and inwardly upon itself to lie inside of said envelope body and adapted to engage the exposed neck band of said shirt when a shirt is in position within said envelope body for preventing 50 accidental shifting of a shirt outward of the notched end of said envelope body, and means formed on said envelope body at the notched end thereof and adapted to engage beneath the outer fold of the collar, of a collar attached shirt, for 55 preventing accidental shifting of a shirt in a direction toward the opposite end of said envelope body.

SAMUEL REICH.
